UNITED STATES PATENT OFFICE.

WILLIAM F. ZIMMERMANN, OF NEWARK, NEW JERSEY, ASSIGNOR TO GOULD & EBERHARDT, OF NEWARK, NEW JERSEY, A CORPORATION OF NEW JERSEY.

BEVEL-GEAR-CUTTING MACHINE.

1,201,417.

Specification of Letters Patent.

Patented Oct. 17, 1916.

Application filed August 24, 1915. Serial No. 47,131.

To all whom it may concern:

Be it known that I, WILLIAM F. ZIMMERMANN, a citizen of the United States, and a resident of Newark, in the county of Essex 5 and State of New Jersey, have invented certain new and useful Improvements in Bevel-Gear-Cutting Machines, and do hereby declare the following specification, taken in connection with the drawings 10 forming part of same, to be a full, clear, concise, and exact description of the invention, and the best mode contemplated to apply the principle thereof, so as to distinguish it from other inventions and to enable 15 any person skilled in the art to which it appertains or with which it is most nearly connected to make, construct, and use the same.

This invention relates primarily to a machine for cutting the teeth of bevel gear 20 wheels and more particularly to a machine for roughing out the teeth preparatory to finishing them upon a planing machine.

The primary object of this invention is 25 to provide an organization which is adapted to operate continuously upon the gear blanks to be cut and wherein it is merely necessary to remove the finished gear and replace same with the uncut blank without stopping the machine.

30 This invention comprises a rotary turret or polyhedron upon which the gear blanks to be cut are mounted, with means to slowly move said polyhedron past the cutters for cutting the metal and then automatically 35 increasing the speed between the cuts and means whereby once during each revolution of said rotary drum or turret all the gear blanks are indexed one tooth.

Other objects will be apparent from, and 40 are incorporated in the annexed drawings, and in the following description which sets forth in detail, certain contrivances embodying means constituting however, but one of the various mechanical forms in which the 45 principle of the invention may be used.

The novelty of the invention will be readily understood from the drawings, which show a construction for practising the invention in its preferred form, and from 50 the following description thereof, and is more specifically pointed out and distinctly claimed in the claims annexed to said description.

In the drawings: Figure 1 is a front ele-

vation of the invention partly in section to 55 clearly illustrate the interior mechanism. Fig. 2 is a side elevation also having certain parts in section. Fig. 3 is a sectional view at XX₁ of Fig. 2. Fig. 4 is an enlarged view of the upper cutter. Fig. 5 is an enlarged view of the operating mechanism for controlling the slow and fast feeds of the 60 turret. Fig. 6 is a side elevation of said operating mechanism. Fig. 7 is a section at ZZ₁ of Fig. 2 showing the indexing mechanism. Fig. 8 is a partial section of the 65 work and cutter spindles.

The main frame 1 has a stanchion 2 at one 70 end thereof, preferably integral therewith. The cutter spindle 3 is rotatably mounted in said stanchion 2 and is connected to the spindle gear 4 by means of the clutch shaft 5, which is slidably keyed to said spindle gear to rotate therewith. Three cutters 6 are keyed to the cutter spindle 3 and separated from each other by the cap bearings 7. Separating bushes 8 which are also keyed 75 to the cutter spindle are introduced between each pair of said cutters so that by tightening the nut 9 all the cutters are clamped 80 securely. The upper part of the cutter spindle 3 is provided with a flange 10 to form an abutment for said cutters.

The cutter spindle 3 is readily removable 85 from its bearings by first removing the cap boxes 7, then raising the shaft 5 by means of the lever 11 which is pivoted at 12 and cooperates with the annular groove 13. The raising of said shaft 5 disconnects same from the clutch face 14 provided on the 90 cutter spindle 3. The purpose of this arrangement is to readily replace another spindle together with the cutters thereon when the cutters in the machine have become dull and need resharpening. The cap boxes 95 7 are so constructed that together with the cavities 15 formed within the stanchion 2 they provide a chamber into which the cooling lubricant may be introduced for the 100 cutters.

The spindle gear 4 is rotatably mounted 105 in the overhanging support 16 which is secured to the upper part of the stanchion 2 by means of suitable bolts 17. The pinion 18 meshes with and rotates said spindle gear 4 and is secured to the vertical driving shaft 19 which is rotatably mounted in the stanchion. To the lower end of said driving

shaft 19 is a bevel gear 20, which meshes with the bevel gear 21 keyed to the horizontal driving shaft 22. The change gears 23 connect said horizontal driving shaft 22 with the pulley or main shaft 24. The pulley 25 is suitably connected to said pulley shaft and receives its motion from any suitable source. The geared connections just described form the rotating means for the cutters.

To the pulley or main shaft 24 is keyed a worm 26 which meshes with the slow feed worm wheel 27. Gears 28 connect said pulley shaft with a feed shaft 29. A worm 30 is keyed to said feed shaft 29 and meshes with the fast feed worm wheel 31. The worm wheels 27 and 31 are rotatably mounted in the main frame to rotate in the same direction, the latter rotating however, at a rate of speed about 7 to 8 times that of the worm wheel 27. The opposing faces of the worm wheels 27 and 31 are provided with clutch teeth 32 and 33 respectively and are alternately engaged by the sliding clutch 34 which is slidably keyed to the turret driving shaft 35. The operation of the clutch controlling mechanism will be hereinafter more fully described. The feed change gears 36 connect said turret driving shaft with the worm or driven shaft 37 which extends along the side of the machine. The worm 38 is slidably keyed to said driven shaft 37 and is held from movement endwise by the bearings 39 on a work slide 40 which is slidably mounted upon guideways 41 formed on the horizontal portion of the main frame. Suitable straps 42 are provided to clamp said slide 40 to the frame. The work table 43 is rotatably mounted in said work carriage 40 and has integral therewith, the worm wheel 44 which meshes with and is rotated by said worm 38. The octagon turret or polyhedron 45 is secured to the work table 43 by means of suitable bolts 46 and is rotatably supported at its upper end in a block 47 which is arranged between the guides 48 of the supporting member 16 and which can be secured to said supporting member by the bolts 49. A series of twenty-four work spindles 50 are rotatably mounted in said turret; three to each face of the octagon. Clamping plates 51 are secured to said turret 45 by suitable bolts to retain said spindles 50. These plates 51 are arranged so that they butt against each other to resist and absorb the circumferential strains imparted thereto by the spindles 50. Each of said spindles is provided with a worm wheel 52 which is partially cut as a helical gear and is preferably made integral with each spindle. The worms 53 which are preferably integral with their shafts 54 are arranged to mesh with said spindle worm wheels 52. The worms 53 are so arranged that each worm is in mesh with two spindle wheels to drive said wheels

on opposite sides. These worms are connected to a suitable indexing mechanism to be hereinafter described.

Each of the spindles 50 is provided with a plate 55 to which the gear blank 56 to be cut is secured. A clamping plate 57 is provided to hold the gear 56 against the plate 55 by means of the stud 58 and nut 59, the stud 58 being secured to said plate 55.

Eight indexing worm shafts 54 are provided, each having three worms 53 chased thereon. To the lower end of four of these worm shafts, gears 60 are secured which mesh with the large indexing gear 61. To the other four indexing worm shafts 54 the gears 62 are secured which mesh with the intermediate gears 63. The intermediate gears 63 are rotatably mounted within the turret 45 and mesh with the index gear 61. The purpose of providing these intermediate or idler gears 63 is to give the proper direction of rotation to each of the worm shafts. The indexing gear 61 is rotatably mounted within the work table 43 and has keyed to its other end, a notched or indexing plate 64, which is periodically engaged by the indexing bolt 65. A cam 66 is secured to and rotates with the work table 43 and is provided with a depression 67 which is arranged to engage with the indexing bolt 65, the latter being mounted in the work slide 40. A spring 68 is provided to keep said indexing bolt 65 in contact with the cam 66 so that when the turret is rotated to a position where the cam depression 67 permits the indexing bolt 65 to move into engagement with the indexing plate 64, the latter will be held stationary while the work table continues to rotate. This connection will cause the work spindles 50 to rotate a predetermined amount dependent upon the number of notches in the indexing plate 64 and the ratio of the gearing 61, 60 and 62 and the ratio of the worms and wheels. The indexing occurs once for each rotation of the turret and takes place when the cutter is not in contact with the gear blanks, which position is more clearly shown in Fig. 8.

The lever 69 is pivoted to the rod 70, which is connected to the indexing plunger 65 so that by moving the lever 69 to the right as seen in Fig. 2, the indexing plunger 65 is withdrawn from contact with the cam 66 and no indexing can take place. A cap 71 secured to the work slide forms an abutment for the spring 68 and the opposing cam surfaces of the lever 69.

The screw 72 which co-acts with the threaded portion 73 on the work slide 40, beneath the indexing bolt 65, is provided to adjust the work turret toward and from the cutters. The screw 72 is rotatably mounted in the frame and is provided with a squared end 74 to coöperate with a suitable crank handle.

To the worm or driven shaft 37 is secured a timing worm 75 meshing with the worm wheel 76 which is rotatably mounted on the side of the stanchion 2 and is provided with 5 two rollers 77 and 88 arranged in different planes to alternately engage with the lost motion lever 78. The lost motion lever 78 which is pivotally mounted upon the rock shaft 79, is provided with a spring plunger 10 80 and a co-operating inclined block 81.

The rock shaft 79 has secured thereto the lever 82 and the clutch fork 83. Clutch pads 84 are provided in said clutch lever 83 and engage the annular groove 85 in the 15 clutch 34. The rollers 77 and 88 are so arranged that when the roller 88 comes in contact with the surface 86 of the lost motion lever 78, said lost motion lever will be moved to the right as viewed in Figs. 2 and 5, until 20 the spring pressed plunger 80 and the inclined block 81 force the lever 82 to the right and thereby engage the clutch 34 with the worm wheel 31. This action will rotate the turret seven to eight times faster than 25 when the clutch 34 is in engagement with the worm wheel 27. When the roller 77 comes in contact with the surface 87 of the lost motion lever 78 the clutch 34 is then forced back into engagement with the worm 30 wheel 27 thereby again slowing up the rotary movement of the turret. The speeding up of the turret occurs each time that the cutter passes from tooth to tooth across the gear blank, and slows down again just 35 before it commences to cut the tooth.

To force large quantities of cooling lubricant into the cutter cavities 15, a pump 89 of the well known centrifugal type is provided and connected to the pulley shaft 24 40 by the bevel gears 90. Conduits in the form of iron pipe 91 connect the cutter cavities 15 with the outlet of said centrifugal pump.

The operation of the entire mechanism is 45 as follows: The work turret or polyhedron is adjusted toward the cutters by means of the adjusting screw 72 and then clamped in position by the straps 42. The cutters receive rotary motion through a gear train comprising change gears 23, bevel gears 21 50 and 20 and gears 18 and 4. The turret is rotated slowly through the worm and worm wheel 26 and 27, change gears 36 and worm 38 and wheel 44, to feed the work past the cutters. This slow feeding motion of the 55 turret will continue until the roller 88 contacts with the surface 86 of the lost motion lever 78 to withdraw the clutch 34 from engagement with the slow feeding worm wheel 27 to engagement with the fast feeding 60 worm wheel 31, thereby imparting rapid motion to the turret between two opposite faces of the gear blank. The fast feeding motion is continued until the roller 77 operates the lost motion lever 78 to move the 65 clutch 34 back again into engagement with

the slow feeding worm wheel. This periodic shifting from slow to fast and vice versa is continual. Once during every revolution of the work turret, all the work blanks are indexed one tooth by means of the cam 66. 70 When the depression 67 of said cam 66 comes opposite to the index bolt 65, the spring 68 forces the bolt into engagement with the notched or index plate 64. This will hold the index plate 64 and the index gear 61 75 from rotation relative to the worm wheel 44 and causes the spindles 50 to make a partial revolution depending upon the number of teeth to be cut in the gear blank. A finished blank is removed whenever the particular 80 spindle has been indexed one half the number of teeth to be cut therein as each passage of the work past the cutter completes two teeth, one opposite the other. When the machine is put in operation the operator 85 places the blank upon various spindles one at a time which are then machined by the cutters until the first blank put upon the turret is completed, which is then removed and another substituted. Thereafter one 90 blank can be taken off for each rotation of the turret without stopping the continuous operation of the machine.

Having described my invention, I claim as new and desire to secure by Letters Patent:

1. In a gear cutting machine the combination of a cutter spindle, a polyhedron, a series of work spindles rotatably mounted in said polyhedron, and means to continuously 100 rotate said cutter spindle and polyhedron relatively to each other.

2. In a gear cutting machine the combination of a cutter spindle, a polyhedron the axis whereof is substantially parallel with 105 the axis of said cutter spindle, a series of work spindles rotatably mounted in said polyhedron, and means to rotate said cutter spindle and polyhedron relatively to each other.

3. In a gear cutting machine, the combination of a cutter spindle, a polyhedron, a series of work spindles rotatably mounted in 110 said polyhedron, and means to continuously rotate said cutter spindle and polyhedron relatively to each other, and means to index 115 said work spindles.

4. In a gear cutting machine the combination of a cutter spindle, a polyhedron, a series of work spindles rotatably mounted 120 in said polyhedron, means to rotate said cutter spindle, means to continuously rotate said polyhedron and means to index said work spindles.

5. In a gear cutting machine the combination of a cutter spindle, a polyhedron the axis whereof is substantially parallel with 125 the axis of said spindle; a series of work spindles rotatably mounted in said polyhedron, means to rotate said cutter spindle, 130

means to rotate said polyhedron, and means to index said work spindles.

6. In a gear cutting machine the combination of a cutter spindle, a polyhedron, a series of work spindles rotatably mounted in said polyhedron, means to rotate said cutter spindles and polyhedron relatively to each other, and means to index said work spindles once during each rotation of said polyhedron.

7. In a gear cutting machine the combination of a cutter spindle, a polyhedron, a series of work spindles arranged to rotate transversely to the axis of said polyhedron, means to continuously rotate said cutter spindle and polyhedron relatively to each other and means to index said work spindles.

8. In a gear cutting machine the combination of a cutter spindle, a series of cutters secured thereto, a polyhedron, a series of work spindles rotatably mounted in each face of said polyhedron correspondingly with said cutters, means to continuously rotate said cutters and polyhedron relatively to each other, and means to index said work spindles.

9. In a gear cutting machine the combination of a cutter spindle, a polyhedron, a series of work spindles rotatably mounted in said polyhedron, means to rotate said cutter spindle, means to slowly rotate said polyhedron during the cutting periods, means to increase the rate of rotation during the non-cutting periods, and means to index said work spindles.

10. In a gear cutting machine the combination of a cutter spindle, a polyhedron, a series of work spindles arranged to rotate transversely to the axis of said polyhedron, means to rotate said cutter spindle and polyhedron relatively to each other and means to index said work spindles once for each rotation of said polyhedron during a non-cutting period.

11. In a gear cutting machine, the combination of a cutter spindle, a series of cutters secured thereto, a polyhedron, a series of work spindles rotatably mounted in each face of said polyhedron, means to continuously rotate said cutters at a constant speed, and means for imparting a cutting and non-cutting movement to said polyhedron for each face thereof.

12. In a gear cutting machine the combination of a cutter spindle, a series of cutters secured thereto, a polyhedron, a series of work spindles mounted in each face of said polyhedron, means to continuously rotate said cutters, means to rotate said polyhedron, and means to alternately increase and decrease the rotative speed of said polyhedron, the number of which alternations of speed is dependent upon the number of faces comprising said polyhedron.

13. In a gear cutting machine the combination of a cutter spindle, a series of cutters secured thereto, a polyhedron, a series of work spindles rotatably mounted in each face of said polyhedron, means to rotate said cutters at a constant speed, means to slowly rotate said polyhedron during a cutting period and means to rapidly rotate said polyhedron during a non-cutting period, said periods recurring for each face of said polyhedron, and means to index said work spindles during a non-cutting period.

14. In a gear cutting machine the combination of a cutter spindle, a polyhedron, work spindles rotatably mounted in said polyhedron, means to rotate said cutters at a constant speed, a shaft, connections between said shaft and polyhedron to continuously rotate the latter and means to alternately increase and decrease the speed of said shaft for each face of said polyhedron.

15. In a gear cutting machine the combination of a cutter spindle, a polyhedron, a series of work spindles rotatably mounted in said polyhedron, a main shaft, connections between said main shaft and cutter spindle to rotate same, a shaft connected to said polyhedron to continuously rotate the latter connections between said shafts to slowly rotate said last mentioned shaft, and other connections between said shafts to rapidly rotate said last mentioned shaft.

16. In a gear cutting machine the combination of a cutter spindle, a polyhedron, a series of work spindles rotatably mounted in said polyhedron, a main shaft, connections between said main shaft and cutter spindle, a shaft connected to said polyhedron to continuously rotate the latter a slow moving member connected to said main shaft, a fast moving member also connected to said main shaft, and connecting said slow and fast moving members to said last mentioned shaft to rotate said polyhedron.

17. In a gear cutting machine the combination of a cutter spindle, a polyhedron, a series of work spindles rotatably mounted in said polyhedron, a main shaft, connections from said main shaft to said cutter spindle, a shaft connected to said polyhedron to continuously rotate the latter a slow moving member connected to said main shaft, a fast moving member connected to said main shaft, and controlling mechanism operated by said last mentioned shaft to alternately connect said slow and fast moving members thereto.

18. In a gear cutting machine the combination of a cutter spindle, a polyhedron, a series of work spindles rotatably mounted in said polyhedron, a main shaft, connections between said main shaft and cutter spindle, a shaft connected to said polyhedron to continuously rotate the latter means to alternately rotate said last men-

tioned shaft fast and slow, and means operated by said last mentioned shaft to control said fast and slow motions.

19. In a gear cutting machine the combination of a cutter spindle, a polyhedron, means to rotate said polyhedron and cutter spindle relatively to each other, a series of work spindles rotatably mounted in said polyhedron, an indexing gear revolvably mounted in said polyhedron and connected to said spindles, and an indexing mechanism operated by said polyhedron to actuate said indexing gear to index said spindles.

20. In a gear cutting machine the combination of a cutter spindle, a polyhedron, means to rotate said cutter spindle and polyhedron relatively to each other, a series of work spindles rotatably mounted in said polyhedron, an indexing gear revolvably mounted in and concentric with said polyhedron and connected to said spindles, an index plate secured to said indexing gear, an index bolt arranged in a stationary portion of the machine to co-act with said index plate, and a cam secured to and rotatable with said polyhedron to control said index bolt.

21. In a gear cutting machine the combination of a cutter spindle, a polyhedron, a series of work spindles rotatably mounted in said polyhedron, an indexing gear independently rotatable and concentric with said polyhedron and connected to said spindles and means to arrest the rotation of said indexing gear.

22. In a gear cutting machine the combination of a cutter spindle, a polyhedron, means to rotate said polyhedron and cutter spindle relatively to each other, a series of work spindles rotatably mounted in said polyhedron, an indexing gear connected to said spindles and arranged to rotate with said polyhedron, and means to actuate said indexing gear independently of said polyhedron thereby indexing said spindles.

23. In a gear cutting machine the combination of a cutter spindle, a polyhedron, means to rotate said polyhedron and cutter spindle relatively to each other, a series of work spindles rotatably mounted in said polyhedron, an indexing gear mounted concentric with said polyhedron and connected to said spindles, said indexing gear arranged to rotate with said polyhedron, and means to actuate said indexing gear independently of said polyhedron to index said spindles.

24. In a gear cutting machine the combination of a cutter spindle, a polyhedron, means to rotate said polyhedron and cutter spindle relatively to each other, a series of work spindles mounted in said polyhedron, an indexing gear rotatable independently of said polyhedron and connected to said spindles, an indexing plate secured to said index gear, a cam secured to and rotatable with

said polyhedron, and a locking bolt actuated by said cam to periodically engage said indexing plate to index said spindles.

25. In a gear cutting machine the combination of a cutter spindle, a polyhedron, means to rotate said polyhedron and cutter spindle relatively to each other, a series of work spindles mounted in said polyhedron, an indexing element connected to said spindles and arranged to rotate with said polyhedron and means to actuate said indexing element to periodically index said spindles.

26. In a gear cutting machine the combination of a cutter spindle, a polyhedron, means to rotate said polyhedron and cutter spindle relatively to each other, a series of work spindles mounted in said polyhedron, geared connections between each of said spindles, an element connected to, and common to all of said geared connections, and means to periodically actuate said common element to index said spindles.

27. In a gear cutting machine the combination of a cutter spindle, a polyhedron, means to rotate said polyhedron and cutter spindle relatively to each other, a series of work spindles rotatably mounted in said polyhedron, wormwheels secured to each of said spindles, a series of worms arranged so that each worm engages two wheels, an element connected to and common to all of said worms, and means to periodically actuate said element to index said work spindles.

28. In a gear cutting machine, the combination of a cutter spindle, a series of cutters secured thereto, a polyhedron, a series of work spindles rotatably mounted in each face of said polyhedron, means to rotate said cutters at a constant speed, and means for continuously imparting a cutting and non-cutting movement to said polyhedron for each face thereof, and means to index said work spindles during a non-cutting period.

29. In a gear cutting machine the combination of a cutter spindle, a polyhedron, a series of work spindles rotatably mounted in said polyhedron, a main shaft, connections between said main shaft and cutter spindle, a driving shaft, connections between said main and driving shafts to slowly rotate the latter, other connections between said main and driving shafts to rapidly rotate said driving shaft, and a driven shaft connected to said polyhedron and driving shaft.

30. In a gear cutting machine the combination of a cutter spindle, a polyhedron, a series of work spindles rotatably mounted in said polyhedron, a main shaft, connections between said main shaft and cutter spindle, a driving shaft, connections between said main and driving shafts to slowly rotate the latter, other connections between said main and driving shafts to rapidly ro-

- tate said driving shaft, a driven shaft connected to said polyhedron, and change speed elements connecting said driving and driven shafts.
- 5 31. In a gear cutting machine the combination of a cutter spindle, a polyhedron, work spindles rotatably mounted in said polyhedron, means to rotate said cutter spindle at a constant speed, a shaft, connections between said shaft and polyhedron comprising change speed elements, and means to alternately increase and decrease the speed of said shaft for each face of said polyhedron.
- 10 32. In a gear cutting machine the combination of a cutter spindle, a polyhedron, a series of work spindles rotatably mounted in said polyhedron, means to continuously rotate said cutter spindle, a shaft, connections between said shaft and polyhedron to continuously rotate the latter, means to alternately increase and decrease the speed of
- said shaft for each face of said polyhedron, and means operable from said shaft to periodically index said work spindles. 25
33. In a gear cutting machine the combination of a cutter spindle, means to continuously rotate the same, a polyhedron, a series of work spindles rotatably mounted in said polyhedron and a variably speeded member 30 connected to said polyhedron to rotate the latter at varying speeds.
34. In a gear cutting machine the combination of a cutter spindle, means to continuously rotate the same, a polyhedron, a series 35 of work spindles rotatably mounted in said polyhedron, a variably speeded member connected to said polyhedron to rotate the latter at varying speeds, and means operable from said member to periodically index said work 40 spindles.

Signed this 23rd day of August, 1915.

WILLIAM F. ZIMMERMANN.
